UNITED STATES PATENT OFFICE.

EUCLID I. LA CHAPELLE, OF BEVERLY, MASSACHUSETTS.

PULLING-OVER MACHINE.

950,179.

Specification of Letters Patent. Patented Feb. 22, 1910.

Application filed July 22, 1909. Serial No. 508,944.

To all whom it may concern:

Be it known that I, EUCLID I. LA CHAPELLE, a citizen of the United States, and resident of Beverly, in the county of Essex and State of Massachusetts, have invented 5 an Improvement in Pulling-Over Machines, of which the following description, in connection with the accompanying drawings, is a specification; like numerals on the drawings representing like parts.

My present invention is a machine for pulling the upper over the last, being one of the steps in lasting boots and shoes.

Certain features of my invention may be 15 used in the assembling operation.

In carrying out my invention I preferably grasp the shoe upper back of the toe of the last, and preferably on or back of the tip line so that the upper is pulled along 20 the lines of the last when being pulled forward and is not raised off from the last. Besides pulling the upper thus lengthwise, I provide means for pulling the edges of the upper at points between the toe and the shank 25 transversely of the last or toward the bottom and at the same time with a slightly forward movement, thereby still further holding the vamp seam to the lines of the last while the vamp is being stretched over the last. When 30 thus stretched over the last the upper is secured at its opposite sides preferably adjacent the tip line. This avoids the usual securing of the extreme toe end of the vamp and hence does away with the subsequent 35 extra operation of pulling out any extreme toe end fastening (or, in McKay shoes, of cutting through the upper around the fastening).

A further distinguishing feature of my invention is that the pulling means is so constructed that it does not pull the leather, at the extreme end of the toe, over the edge of the last, but instead thereof pulls said leather forward without bending it over the last. 45 I grasp the upper back from the toe, preferably at or back of the tip line, with a combined downward and forward movement so that the upper is held snugly down approximately against the last throughout the entire 50 pulling movement. Bearing in mind that the toe of the last is usually higher than the instep portion of the last, it will be evident that when the pull on the upper is applied ahead of the toe or at the extreme forward 55 end of the upper, the upper will thereby ob-

viously be pulled away from the last just back of the raised toe portion, whereas by grasping the upper back of this raised toe portion at said hollow or lower portion of the last which is approximately at or back 60 of the tip line, and then applying a forward pull combined with a downward pressure against the last, the upper will obviously not be raised but will be compelled to follow the lines of the last. The result is that in the 65 subsequent steps of the lasting operation the usual severe strain which frequently tears the upper is not necessary, and also in the still subsequent operation just before the welt sewing, when the tacks are withdrawn 70 from the upper, there is no tendency for the upper to spring back out of place as heretofore, because the upper has not been unduly strained away from the last at the pulling over operation and when the fastenings 75 were inserted. In other words, my invention aims to bring a uniform strain in natural directions at all points of the upper so that no one point of the upper is distorted or overstrained.

While it is possible to employ the usual grippers in carrying out my invention, simply giving them new directions and timing of movements, I prefer to do away with the ordinary grippers and employ entirely new 85 mechanism throughout. Also while the invention, in its broader aspects, is not limited as to the number of separate pulling means employed, I have found one pulling means at each side and one between at the top sufficient, in connection with proper heel-seat 90 and shank forming or holding mechanism. Also while my invention is not limited to the location of the pulling means, as for instance, when jaws are employed, they may 95 be located at the ball or farther toward or from the shank and there may be any number of them and they may have various turning movements besides the simple pulling movement, but preferably I employ simply 100 pulling jaws or devices located at the rear corners of the tip. This latter will be sufficient in some cases without the intermediate top jaws or pulling devices, as for instance when said intermediate jaw or its equivalent 105 tip corner jaws curved to the last and extending practically to the vamp seam, have been previously used on an assembling machine and the shank only has been wiped in and fastened, in which case the subsequent 110

pulling over operation may be practically carried out simply by the side jaws or pulling devices at or back of the corners of the tip.

5 Further advantages, construction and operation of my machine will be pointed out in the course of the following description, taken with reference to the accompanying drawings, in which I have shown a preferred 10 embodiment of the machine.

In the drawings, Figure 1 is a view in side elevation, parts being broken away for clearness of illustration; Fig. 2 is a bottom plan view of a shoe and last showing the vamp 15 pulled over by my machine; Fig. 2^a is a front elevation of one of the cams; Fig. 3 is a view in side elevation of a part of the pulling mechanism at the limit of its upward movement; Fig. 4 is a transverse section on the line 4—4, Fig. 1; Fig. 5 is a 20 side view of a portion of the heel and shank forming and holding devices; Fig. 6 is a view looking toward the left at Fig. 5; Fig. 7 is a section on line 7—7, Fig. 5; Fig. 8 is 25 a section on line 8—8, Fig. 5; Fig. 9 is a longitudinal sectional detail of the upper grippers; Fig. 10 is a section on line 10—10, Fig. 9; Fig. 11 is a sectional detail of the 30 forepart support or rest and sole-adjusting means; and Fig. 12 is a bottom plan view looking at Fig. 11 toward the underside.

On a suitable pedestal 1 journaled in a head 2 is a main driving shaft 3 which carries a cam 4 for operating the side pincers 35 hereinafter described, a cam 5 for operating the upper-pulling mechanism, a cam 6 for operating the tack-feeding devices, a cam 7 for operating the sole-adjusting devices, a cam 8 for actuating the side tackers 40 (through mechanism not shown), and a cam 9 for operating the forepart support. The tacking mechanism may be of any usual or preferred kind, being herein shown as substantially the same as in the McFeely patent 45 No. 663,777, for tacking only at the opposite sides of the shoe and comprising in general a hopper 10 whose agitator is operated by a pinion 11, segment lever 12 and rod 13, the latter being connected with the slide 14 carrying a cam roll 15. The tacks 50 are delivered through two chutes or race-ways 16, one at each side of the machine, only one thereof being herein shown, and the tack-driving mechanism is indicated at 55 17 for driving tacks at each side of the shoe as indicated at 18, 19, Fig. 2 (see also Fig. 81 of the McFeely patent, my machine omitting, however, the toe tack and its driving mechanism and employing only the two side 60 tackers). These side tacking devices are pivoted at their upper ends at 20 and swung toward and from each other into and out of tack-driving position at the opposite sides of the shoe by being operated by a hand lever 65 21 or automatically by the cam 8, all as in

said patent and hence not herein shown or explained in further detail. The vamp 22 on a last 23 in usual manner is placed in a heel rest or support and shank shaper consisting of two side plates or wings 24, 25, 70 best shown in Figs. 1, 5 and 6. The toe of the last rests against a toe rest or projecting finger 26 secured to and projecting forward from an extension 27 of the forepart support or rest and sole adjuster 28. The latter 75 consists, as best shown in Figs. 1, 4, 11, and 12, of a block or carrier 29 provided with opposite grooves 30, 31, in which reciprocate slides 32, 33 provided at their forward ends with sole-engaging feet 34, 35, herein shown 80 as preferably secured immovably to said slides, which are retained in sliding position by side ribs 36 and operated by engagement of their racks 37 with pinions 38, 39 fast on a shaft 40. Loose on the shaft is a sleeve 85 41 provided at one end with a pinion or gear 42 and at its other end with a friction disk 43, said gear meshing with a rack bar 44 mounted to slide longitudinally and actuated by the engagement of its cam roll 45 90 with the cam 7 against which it is held by a spring 46 secured at one end to a pin 47 depending from said rack bar and at its other end to the frame of the machine at 48.

Bearing against the disk 43 is a friction 95 disk 49 splined on the shaft 40 and normally held in yielding driven engagement with said disk 43 by a spring 50 surrounding said shaft 40 and held under desired tension by a collar 51 connected by a flanged sleeve 100 52 to a hand tension wheel 53 threaded on the outer end 54 of said shaft 40. Thus when, the last with its innersole (in this case a McKay innersole) having been put in position, the upward movement of the 105 feet 45 is caused by the forward movement of the rack 44, the frictional or yielding connection between said rack bar and the actuating shaft 40 permits said feet to halt as soon as the innersole strikes the stop 26, 110 or in other words coincides with the end of the last. The yielding connection at 43, 49 permits the rack bar 44 to complete its cam-actuated movement after the shaft 40 has come to a halt. The rack bars are stopped 115 on their return movement by a pin 55.

At each side of the block 28 on the adjacent front side of the frame 2 are opposite ways 56 in which travel the sliding ends 57 of a carriage 58 in which are mounted longitudinally extending pins 59 which serve as the pivots of blocks 60 to each of which is pivoted at 61 an arm 62 provided with two lugs 63, 64 between which extends the free end of a spring 65 fast at its other end to 125 the head of the pin 59, thereby normally maintaining said arm 62 in an intermediate forward position, each arm being held yieldingly outward and upward at its outer ends by a spring 66 carried by the arm and 130

bearing against the face of the adjacent block 60, thereby normally maintaining the ratchet teeth 67 of each of said arms 62 out of engagement with the 5 opposite teeth 68 of the carriage 58, said teeth being best shown in Figs. 7 and 8. On the outer ends of said arms 62 is mounted a double ended pawl or, more properly, opposite pawls 69, 70 rigidly connected by 10 a bar 71 to which on the opposite side of the adjacent ends of the arms 62 are secured by any suitable means, as by pins 72, posts 73 carrying a transverse plate 74 whose outer arms 75 support and guide rods 76 pivotally 15 connected at their inner ends at 77 to the side plates or wings 24, 25, supported by segment arms 78 pivoted at 79 to the opposite ends of said plate as best shown in Fig. 5, said wings 24, 25 and arms 78 being held 20 inwardly to hold the work by springs 80 on the rods 76. The said plates or wings 24, 25 are inwardly curved at 81 and outwardly curved at 82, being curved toward each other again at their rear ends at 83, 25 with the result that when the work is placed against the flaring outer ends 84 and either pressed inwardly toward the pivot 79 or held stationary and the mechanism pressed upwardly over the work, the inwardly bulging portions 81 of the wings crowd against 30 and rub toward along the edges of the heel-seat and gradually rub inward and embrace the shank part of the vamp and vamp seam. The final position of the work is preferably 35 with the extreme end of the heel resting against the inner curve of the arms 78 just in front of the pivot 79.

The wings or shank and heelseat forming plates 24, 25 are preferably sufficiently wide, 40 see Fig. 5, to embrace not only the counter and shank proper but reach up to and over the vamp seam so that the placing of the work in position will have to hold the vamp seam to the lines of the last prior to and 45 during the forward pull of the vamp by the pulling mechanism to be described. This mechanism is normally held upward by opposite springs 85, one on each side of the pedestal 1, mounted on rods 86 secured at 50 their upper ends to lugs 87 of the carriage 58 and at their lower ends loosely sliding in brackets 88 against which the lower ends of the springs bear, their upper ends engaging adjustable stops 89.

55 At each side of the carriage toothed locking bars 90 are provided, secured rigidly to the frame by arms 91 opposite the pawls 69, 70 to co-operate therewith in locking the carriage and work held thereby in desired position. Vertical slots 92 are provided at 60 about the middle of these bars, extending longitudinally thereof, so that when the pawls 69, 70 are in their normal intermediate position they can move freely up and down 65 without engaging in any way the teeth of

the locking bars 90, but when moved slightly sidewise in either direction they instantly engage and are locked by said teeth.

When the work is first placed in the wings or holders 24, 25, the pawls 69, 70 being in 70 their intermediate position, the spring 85 moves or holds the work pressed tightly against the rest 26 whatever the size of the last, and, the shoe having been thus correctly positioned as to height, the operator swings 75 the heel-part one way or the other according to the crookedness of the last, whether a right or left, so as to bring the forepart of the last and work into correct relation with the pulling mechanism, and this swinging 80 movement of said heel-part causes said pawls 69, 70 to move laterally in one direction or the other, thereby being locked against vertical movement either up or down.

85 As already stated, the forepart pulling mechanism consists of side pullers preferably in the form of pincers, at least one at each side, and preferably a third pulling device in the form of pincers arranged to pull 90 the top of the vamp, engaging at or back of the tip line and following approximately along the surface of the last as the vamp is pulled forward. The side pincers or grippers are shown in detail in Fig. 9 and preferably are the same as in the patent before mentioned, comprising opposite jaws 93, 94, the former fixed and the latter movable, being pivoted at 95 and normally held closed by a pivoted latch 96 and spring 97. The 100 fixed jaw 93 is at the end of a tubular member 98 within which is mounted an endwise movable shank 99 supported at its upper end for universal movement by a ball and socket joint 100 and at its lower end having 105 a projection 101 which controls the opening and closing movements of the jaw 94 which is pivotally carried by links 102 pivoted at their upper ends to a block 103 having a wedge-shaped tongue 104 for co-operating 110 with clutch rolls 105 normally held up by springs 106 to a position just above the top of the tongue 104 bearing against the adjacent shoulder 107 on the shank 99, said block being normally held up by a heavy spring 115 108. The latch 96 engages a sliding block 109 which co-operates in controlling the movable jaw 94. The jaw 93 is held against downward movement at the proper times by the engagement of the shoulders 110 with an extension 111 of the frame. These side pincers or grippers are otherwise free to move with their shanks inwardly and outwardly and forward and backward over the last as required for the pulling operation.

The upward movement is communicated to these side grippers by opposite levers 112, 113, both actuated from the same slide 114 whose roll 115 travels in the cam 4. The rear end 116 of each lever is connected with 120 125 130

the slide 114 through two collars 117, 118 mounted on a rod 119 and the former held yieldingly by a spring 120 whose tension is regulated by a thumb nut 121. As the grippers move upwardly they are also directed forward by the engagement of studs 122 projecting from the adjacent lower end of the tubular member 98 in engagement with a path cam 123 deflected forward at its lower 5 end, provided in a guide casing 124 which partly surrounds the gripper shanks and is free to slide laterally or transversely of the shoe, having a directing rib or tongue 125 to slide in a groove 126 on the frame of the machine, so that as the grippers are moved upwardly by their levers 112, 113 they are simultaneously moved forward by the cam grooves 123. When the grippers have strained the vamp upward and forward to 10 the desired extent they are moved inwardly so as to bend the leather over the opposite edges of the last in position to be tacked and are simultaneously released from the leather, by the lateral inward swinging movement 15 of the tack-driving devices 17 previously mentioned, which, as they swing inwardly in order to bring their driving ends (which also serve as wipers) into position over the last, strike against the gripper mechanism so as to swing the grippers inwardly, and at the 20 same time because of their engagement with the latches 96, release the grippers from the vamp, all substantially as shown and described in the patent before mentioned. The 25 middle grippers which operate along the middle or center of the vamp at or back of the tip seam, or at least back of the toe of the last and vamp, are herein shown as also of the pincer kind substantially the same, in 30 this respect, as the side grippers, comprising jaws 127, 128. The jaw 127 is hinged at 129 to the forward end of a centrally arranged lever 130 fulcrumed at 131 and pivotally connected at 132 with a vertically movable 35 slide 133 carrying a cam roll 134 in engagement with the cam 5. The hinge joint 129 is a knuckle joint, and a spring 135 normally holds the jaw 127 against the last, said spring engaging at its opposite ends lugs 136, 137 on the jaw 127 and lever 130 respectively. The jaw 128 comprises two members, 138, 139 pivoted together at 140 by the same kind of joint as the joint 129, which is similarly spanned by a spring 141 engaging lugs 142, 143, of said two parts of the 45 jaw, for holding the part 138 yieldingly toward the work and against the jaw 127 when in gripping position. A slot 144 in the rear part 139 of the outer gripper jaw receives a 50 block 145 which is pivotally supported by the jaw 127 and is normally locked by a dog 146 which is guided in a branch slot 147 from the main slot 144 and held yieldingly forward by a spring 148, being retained by a 55 thumb nut 149, but when the gripper jaws 60

127, 128 are moved toward by the upward swing of their carrying lever 130, a roll 150 projecting from the dog 146 slides along the cam edge 151 of a stationary plate 152 secured to the extension 111 of the frame of 70 the machine, thereby releasing the dog 146 from engagement with the block 145 at the end of the vamp stretching or toward pulling movement.

The plate or upper member 139 of the 75 outer jaw 128 has a rearwardly extending arm or portion 153 provided with a roll 154 which travels in a cam groove 155 in the stationary plate 152 offset at its lower end 156 and concentric with the center of swinging movement 131 throughout its upper extent, operating to place the jaws under gripping pressure with relation to the leather when the lever 130 is raised by the cam 5, the lever 130 being shown in an intermediate position, Fig. 1, the deflected portion 156 operating to swing the outer jaw toward to open the gripper when the lever 130 reaches its lowest position. The instant the gripper starts on its upward movement, the cam 155 operates through the roll 154 and arm 153 to swing the outer jaw on the block 145 as a pivot so as to close the jaw 128 against the jaw 127 with a clamping pressure against the interposed leather, which is maintained during the desired toward stretching or forward pulling over movement of the gripper on the leather, until the two jaws are released from each other by the disengagement of the dog 146 of the outer 100 jaw from the block 145 of the inner jaw caused by the lifting action of the cam 151 against the roll, 150 of said dog, whereupon the outer jaw 128 stops its toward movement, inasmuch as it is no longer positively connected to the inner jaw 127 and is halted by the engagement of its leather-engaging end with the leather, and the continued upward swing of the lever 130 meanwhile gradually withdraws the inner jaw 127 from beneath the vamp, the pivot block 145 sliding idly along the slot 144. During this toward pulling movement the springs 135 and 143 hold the two jaws 127 and 128 yieldingly toward the last so as to hold the vamp 110 against the last and follow the lines of the last, and at the same time the cam 9 swings the forepart support 28 so as to force the last toward these jaws and thereby cooperate therewith in maintaining the desired relation. The member 28 is subsequently returned to its original position by a spring 115 120 125 130 135 140 145 150 155 160 165 170 175 180 185 190 195 200 205 210 215 220 225 230 235 240 245 250 255 260 265 jaw yields under the action of spring 141. When the two jaws are automatically released from each other, as explained, this pad 158 and the engagement of the roll 154 with the stationary plate 152 coöperate to prevent any further movement of the jaw 128 while the jaw 127 is being withdrawn from beneath the vamp. The middle gripper, *i. e.* the mechanism terminating in the jaws 127, 128, preferably starts its pull directly in line with the vamp seam so as to bring its greatest strain lengthwise of the last in line with said vamp seam, this being desirable for the most perfect pulling over operation. This strain is even on both sides and is accomplished equally along the vamp seam at each side of the last and throughout the whole length of said vamp seam. This is especially valuable in working on blucher-style shoes, and constitutes one of the most important and novel features of my machine. In very heavy shoes I preferably grip back far enough to engage the front ends of the shoe top directly at the vamp seam itself so as to bring practically all the initial strain directly on the seam without stretching the vamp, the latter being then stretched by the subsequent toeward movement of the side grippers, after the under jaw 127 of the middle gripper has been withdrawn from beneath the vamp. At the end of the forward vamp pulling movement the under jaw 127 of the pincers has passed entirely out from under the vamp so as to permit the leather to lie tight against the last under the combined action of the jaw 128 and the side grippers previously described together with the coöperating pressure and movement of the forepart support just described. At the end of the upward movement of the lever 180, the parts carried at the forward end of the latter occupy the position shown in Fig. 3. As a rule the vamp will be engaged just back of the tip seam and the outer jaw 128 does not slide on the leather but simply coöperates with the inner jaw 127 to strain or pull the leather lengthwise and hold it on the last at all times, both during the pulling movement of the middle gripper as well as during the pulling movement of the said grippers.

At the start the operator places the forepart of the vamp at the middle portion thereof between the jaws 127 and 128 and the side edges of the vamp between the open jaws of the side grippers. During the forward straining of the vamp by the middle gripper, the side grippers remain open and the side edges of the vamp are free to shift forward between the jaws of said side grippers under the straining movement of the middle gripper, and just as the middle gripper stops its forward pull on the vamp the side grippers close on the adjacent edges of the vamp, and as soon as the inner jaw

127 of the middle gripper has moved out from beneath the vamp so that the latter is free to set itself tight against the last, the side grippers begin their pulling movement with the combined bottomward and toeward or diagonal straining movement previously described. 70

As already stated, as soon as the final stretching of the vamp or pulling over movement is completed the tacks 18, 19 are 75 driven at the opposite sides of the toe as shown in Fig. 2, thereby retaining the vamp in its pulled over position on the last, the jaw 128 of the middle gripper aiding materially in holding the last rigidly during 80 the driving in of these fastenings at the sides of the toe part, and also aids in making it impossible for the vamp to shift from its stretched position and snug engagement against the last until said holding tacks have 85 been driven.

According to my invention there is no necessity of pulling the extreme toe end of the vamp and no necessity of securing said extreme toe end with the usual toe tack. Of course a pull at the extreme end and a toe tack may be employed if desired after the part of the vamp back of the toe of the last has been set on the last and the operations have been performed which have been described above as constituting the main features of my invention, but I desire it clearly to be understood that my invention makes it feasible to do away with the pull on the extreme toe end of the vamp and with the 90 usual tack in said extreme toe end. This not only makes a material saving in time, but it avoids the frequent cause of mutilating or crippling shoes, due to applying the longitudinal stretching pull on the vamp at 105 the toe end or end of the tip of the vamp which frequently results in tearing the leather and straining the tip seam. When the pulling over strain is applied at the extreme toe end of the vamp, not only does the 110 strain come in front of the tip seam, thereby tending to open said seam, but the pull when applied at this point necessarily lifts or raises the vamp away from the last between the top of the toe and the throat of the vamp 115 at the instep, and also tends to pull in and bind the ends of the quarters on a blucher shoe without getting the desired straightforward pull on the vamp from the heel-seat along the counter and at the sides of the last. Furthermore by having my middle gripper, arranged as shown and described, see Fig. 9, the gripping jaws can be wide enough to get in line with the vamp seam at 120 the opposite sides. Also by having the middle gripper engage the vamp back from the toe in the hollow which always exists in a last between the raised top of the toe end of the last and the base of the instep of the last, 125 130

and by having said middle gripper exert its pull forward in connection with a simultaneous downward or last-ward pressure, the vamp is kept to the lines of the last during said pull, and is not strained away from the shank and ball of the last as is the case when the pull is at and over the toe end of the last. Also by applying the pulling pressure of my middle gripper at the region mentioned and in the manner mentioned, and by maintaining the vamp held toward and against the last while the side grippers exert their bottomward and toeward pull on the side edges of the vamp, the latter is never subjected to the usual unequal strains which have heretofore proved liable to twist the side of the vamp at the shank and ball region, and a still more important result of this special combined operation of the middle gripper and side grippers, or in other words, of setting the top of the vamp back of the toe of the last onto the last before the longitudinal side edges of the vamp have been fully stretched, is that there is no overstraining of the leather at and just in front of the ball or widest portion of the vamp and shoe as heretofore in the usual side lasting operation. Said overstraining at the region mentioned is what produces the overtight, strained appearance of the leather, and tendency to wrinkle in many shoes just back of the tip seam.

As long as the vamp is strained, set, or held toward the last at the region between the toe end of the last and the instep before or during the longitudinal pulling over movements on the vamp, I consider that my invention, in the broadest aspect of this feature thereof, is availed of. For instance by omitting the under jaw 127 of the middle gripper, the outer jaw 128 serves simply to press and hold the vamp down against the last at the region mentioned or hollow back of the top of the toe, and the side grippers would then be depended upon for effecting the toeward straining movement of the vamp, supplemented or not by a hand wiping operation at the toe end of the vamp. In such case the object would be to use the middle gripper for exerting a mild pull or external rubbing action on the vamp last-ward down the longitudinal center of the vamp toward the toe, prior to straining the vamp lengthwise by means of the side grippers. This would be particularly useful in handling those vamps which do not fit the last properly, but are larger or longer than the last. In the general run of a shoe factory it often happens that the right size and style of upper is not applied to the intended last and hence some of the uppers are extra large longitudinally so that the vamp seam can then easily be set in proper position on the last at the instep with a mild lengthwise strain or rubbing movement such as men-

tioned, and this same remark applies to vamps which have been previously pulled lengthwise in the shank at the assembling operation. This external mild straining of the vamp may be accomplished either by removing the under jaw (preferably when there are many such cases to handle) or by simply resting the entire middle gripper externally of the vamp (preferably when there are only a few such cases to handle in the general run). In the latter case both jaws of said middle gripper press the vamp last-ward and set the vamp and vamp seam to the lines of the last at the instep by a mild forward pull or rubbing action on the vamp (or on the lining, if a turn shoe) prior to the straining of the vamp lengthwise by the side grippers. In such case, the jaw 128 continues to hold the vamp on the last to prevent any receding movement or strain of the vamp toward the heel, after the under jaw 127 has passed forward away from the toe, said jaw 128 preferably continuing so as to hold the vamp during the applying of fastenings at the bottom thereof.

A further feature of my invention, which is also to be particularly noted, resides in providing means for releasing the toeward straining movement on the vamp before the side grippers have completed their bottomward pull on the last (or the opposite movement of the last toward the vamp). Also the provision of means (in the preferred construction herein shown, consisting of the wings or holding plates which embrace the counter and heelseat) for straining forward and holding the counter and the shank of the last, in connection with means for holding the forepart of the vamp bottomward toward the last in the hollow back of the toe, and means for securing the vamp to the sole while thus held at a point or points between the toe and the heelseat. Also the provision, in connection with means for lengthwise straining the vamp, of means for forming and holding the heelseat and shank part including the vamp seam and the vamp, to the last before or during said lengthwise straining of the vamp.

Having described my invention, what I claim as new and desire to secure by Letters Patent is:

1. In a machine of the kind described, mechanism for straining a vamp longitudinally, including automatic, power stretching means engaging the vamp back of the extreme toe-end of the last, having a forward pulling movement substantially in the direction of the vamp seam for stretching the vamp of said toe-end prior to the stretching of the vamp at said toe-end, and co-operating means to hold said toe-end of the last against said straining movement.
2. In a machine of the kind described, mechanism for straining a vamp longitudinally,

dinally, including automatic, power stretching means engaging the vamp at or back of the tip seam of the vamp, having a forward pulling movement terminating back of the toe-end of the last, and coöperating means to hold an entire last from and including its extreme toe-end to its heel-end against said straining movement.

3. In a machine of the kind described, mechanism for straining a vamp longitudinally, including means holding the vamp toward the last at the hollow region back of the toe, and simultaneously stretching the vamp lengthwise back of the toe of the last, prior to the straining of the extreme toe-end of the vamp and prior to the fastening of the vamp to the forepart of the last.

4. In a machine of the kind described, mechanism for straining a vamp longitudinally, including means holding the vamp toward the last at the hollow region back of the toe, and simultaneously stretching the vamp lengthwise, means for forming the shank part of the vamp toward and about the last, and means for subsequently fastening the vamp to the forepart of the last, all while the vamp is under lengthwise strain.

5. In a machine of the kind described adapted to handle an entire vamp having a complete toe-portion, mechanism for straining said vamp longitudinally, including stretching means for engaging the top of the vamp back of said toe portion at or back of the tip seam thereof.

6. In a machine of the kind described, mechanism for straining a vamp longitudinally, including stretching means for engaging the top of the vamp at or back of the tip seam, and means for simultaneously moving said stretching means under bottomward pressure on the vamp.

7. In a machine of the kind described, mechanism for straining a vamp longitudinally while being shaped on a last having an entire toe-end, including automatic stretching means for engaging the top of the vamp at or back of the vamp to the lines of the last while under the influence of said automatic stretching means.

8. In a machine of the kind described adapted to handle an entire vamp having a complete toe-portion, mechanism for straining a vamp longitudinally while being shaped on a last having an entire toe-end, including automatic stretching means for engaging the top of the vamp at or back of the tip seam, and coöperating means for shaping the vamp at the shank and forepart to the lines of the last while under the influence of said automatic stretching means.

9. In a machine of the kind described, means to shape a vamp at the shank to the

lines of a last, and mechanism to hold the vamp bottomward at the forepart of the last and simultaneously stretch the vamp lengthwise substantially in the direction of the vamp seam.

10. In a machine of the kind described, means to stop the last at a predetermined point, and coöperating stretching mechanism, including means adapted to engage the vamp at or back of the tip seam, and controlling mechanism limiting the pulling movement of said engaging means to a predetermined distance from the toe.

11. In a machine of the kind described, means to stop the last at a predetermined point, and coöperating stretching mechanism, including means adapted to engage the vamp at or back of the tip seam, controlling mechanism limiting the pulling movement of said engaging means to a predetermined distance from the toe, and means to adjust said stopping means.

12. In a machine of the kind described, the combination with vamp-stretching means to stretch the vamp longitudinally, of heel-seat shaping means, including holding mechanism embracing and firmly holding all parts of the upper about the counter and having a shank engaging and shaping portion.

13. In a machine of the kind described, forward stretching means for maintaining a vamp and its vamp seam under tension at or back of the tip seam while leaving the tip without strain, means for holding the heel-seat and shank portion in shaped position toward the last, and means for fastening the forepart of the vamp to the last while so held.

14. In a machine of the kind described, vamp pulling means for engaging the top of the vamp and stretching the same toewards, means to engage and stretch the vamp bottomward, and releasing means to release the first mentioned stretching means before the completion of the movement of the second stretching means.

15. In a machine of the kind described, means for forming and holding the heel-seat and shank part of an upper including means for relatively moving said means and the upper longitudinally of the last, means engaging said upper along the vamp seam and means to move said engaging means with a vamp stretching movement.

16. In a machine of the kind described, the combination with means for engaging and stretching the top of a vamp toewards while leaving the top without strain, of side grippers having bottomward and toewards stretching movements while the vamp is so held by said means and prior to the stretching of said tip.

17. In a machine of the kind described, a toe rest to limit the toewards movement of a

- last in the machine, and heel-seat and shank forming mechanism, held under strong yielding pressure toward said rest, for engaging with a sliding shaping movement
- 5 the counter portion and shank portion of a vamp and holding both of said portions in shaped position toward the last while under the lengthwise frictional strain.
18. In a machine of the kind described, a toe rest to limit the toeward movement of the last in the machine, and heel-seat and shank forming mechanism, held under strong yielding pressure toward said rest, for engaging with a sliding shaping movement
- 10 the counter portion and shank portion of a vamp including the vamp seam and holding said counter portion, said shank portion and said vamp seam in stretched and shaped position toward the last while under
- 15 said lengthwise frictional strain.
19. In a machine of the kind described, a toe rest to limit the toeward movement of a last in the machine, and heel-seat and shank forming mechanism, held under
- 20 strong yielding pressure toward said rest, for engaging with a sliding shaping movement the counter portion and shank portion of a vamp, said mechanism including opposite side shaping wings curved to the
- 25 shape of the vamp and to the shape of the shank along the sides thereof, and tension means normally pressing said wings hard against the vamp and the shank.
20. In a machine of the kind described, a toe rest to limit the toeward movement of a last in the machine, and heel-seat and shank forming mechanism, held under strong yielding pressure toward said rest, for engaging with a sliding shaping movement
- 30 the counter portion and shank portion of a vamp, said mechanism including shaping wings pivotally supported intermediate their length for engaging the vamp along the sides thereof and tension means normally pressing said wings hard against the vamp.
21. In a machine of the kind described, a toe rest to limit the toeward movement of a last in the machine, and heel-seat and shank forming mechanism, held under
- 35 strong yielding pressure toward said rest, for engaging with a sliding shaping movement the counter portion and shank portion of a vamp, said mechanism including shaping wings pivotally supported intermediate their length for engaging the vamp along the sides thereof, tension means normally pressing said wings hard against the vamp, and pivotal supporting means for said
- 40 opposite wings permitting them to have a bodily edgewise pivotal movement.
22. In a machine of the kind described, a toe rest to limit the toeward movement of a last in the machine, and heel-seat and shank forming mechanism, held under
- 45

strong yielding pressure toward said rest, for engaging with a sliding shaping movement the counter portion and shank portion of a vamp, said mechanism including shaping wings pivotally supported intermediate their length for engaging the vamp along the sides thereof, tension means normally pressing said wings hard against the vamp, pivotal supporting means for said opposite wings permitting them to have a bodily edgewise pivotal movement, and means permitting said wings and the work engaged thereby to swing angularly in the normal plane of the last in a direction perpendicular to the last mentioned pivotal movement.

23. In a machine of the kind described, a toe rest to limit the toeward movement of a last in the machine, and heel-seat and shank forming mechanism, held under strong yielding pressure toward said rest, for engaging with a sliding shaping movement the counter portion and shank portion of a vamp, said mechanism including shaping wings pivotally supported intermediate their length for engaging the vamp along the sides thereof, tension means normally pressing said wings hard against the vamp, pivotal supporting means for said opposite wings permitting them to have a bodily edgewise pivotal movement, and means permitting said wings and the work engaged thereby to swing angularly in the normal plane of the last in a direction perpendicular to the last mentioned pivotal movement.

24. In a machine of the kind described, gripper means for stretching a vamp, including two gripping members, and operating mechanism maintaining said members in gripping relation to the work for stretching the latter and permitting the inner member to move out of gripping relation while the outer member still maintains its gripping relation with respect to the work.

25. In a machine of the kind described, gripper means for stretching a vamp, including two gripping members, and operating mechanism maintaining said members in gripping relation to the work for a predetermined extent of forward movement and permitting the inner member then to continue said movement out of gripping relation with the outer member, and maintaining the outer member in continuous holding engagement with the work.

26. In a machine of the kind described, gripper means for stretching a vamp toewards, including two gripping members, and operating mechanism maintaining said members in gripping relation to the work for a predetermined extent of the toeward stretching movement and permitting the

inner member then to continue said movement out of gripping relation with the work and with the outer member, and maintaining the outer member in continuous holding engagement with the work during said separate continued movement of the inner member.

27. In a machine of the kind described, gripper means for stretching a vamp, including two gripping members, and operating means for simultaneously separating said members from gripping relation with the work prior to the final disengagement of the work by said gripper means.

15 28. In a machine of the kind described, gripper means for stretching a vamp, including an outer gripping member and an inner gripping member normally engaging and gripping the work between them, and 20 operating mechanism, including means maintaining a constant inward pressure of said gripper means toward the last, and means moving said two members forward with a preliminary stretching movement 25 and then permitting them to separate, the inner member moving out from under the work while the outer member still holds the work.

29. In a machine of the kind described, 30 gripper means for stretching a vamp, including an actuating lever, a gripping jaw pivoted thereon, a second jaw movably mounted on said first jaw, and means requiring said two jaws to move together with 35 said arm during their stretching movement, the first mentioned jaw having thereafter an independent movement away from the other jaw.

30. In a machine of the kind described, 40 gripper means for stretching a vamp, including a main actuating device, a jaw secured thereto, and a second jaw comprising a rear part having a pin and slot connection to said first jaw, a forward gripping part

pivoted to said rear part, and spring means 45 normally holding said forward gripping part toward the work, locking means normally holding said two jaws together for their stretching movement, and releasing means unlocking said two jaws at the end of said 50 stretching movement.

31. In a machine of the kind described, automatic power-actuated means for engaging a vamp with a rubbing action toward the toe of the last back of said toe 55 of the last, and additional means for straining said vamp lengthwise.

32. In a machine of the kind described, means for holding a vamp lastward back of the toe of the last, additional means for 60 straining said vamp lengthwise, and operating means maintaining said holding means in external contact with the vamp during lengthwise straining of said vamp.

33. In a machine of the kind described, 65 mechanism for straining a vamp, including automatic power-actuated means for externally engaging and holding the central longitudinal portion of a vamp against the last back of the toe of the last, and means 70 for fastening the vamp to the forepart of the last while so held.

34. In a machine of the kind described, 75 automatic power-actuated means for engaging with a rubbing action a vamp and pressing said vamp lastward and toeward back of the toe of the last while leaving the extreme toe end of the vamp without strain, and means for turning said vamp over the edge of the last.

In testimony whereof, I have signed my name to this specification, in the presence of two subscribing witnesses.

EUCLID I. LA CHAPELLE.
